UNITED STATES PATENT OFFICE.

REUBEN D. COY, OF GLENCOE, ILLINOIS.

PRINTING-PRESS.

1,022,406.

Specification of Letters Patent.

Patented Apr. 9, 1912.

Application filed June 17, 1910. Serial No. 567,473.

To all whom it may concern:

Be it known that I, REUBEN D. COY, a citizen of the United States, residing at Glencoe, in the county of Cook and State of Illinois, have invented certain new and useful Improvements in Printing-Presses, of which the following is a specification.

My invention relates to a printing press of the type which prints upon a continuous web, and the invention has for its object to provide certain new and improved devices, constructions and arrangements, to be hereinafter described, which are by preference employed conjointly in the manner shown, and when so employed have a particular coöperative relationship and a particular utility, as will be apparent, and constitute a web press having certain novel features and capacities; but which devices, constructions and arrangements may nevertheless be employed separately, in presses constructed differently from that here shown, or as improvements upon other forms of presses now in use.

The press of the present invention in its general characteristics follows the arrangements shown in my Patent No. 863,591, granted August 20, 1907, in which the printing surfaces, or coöperating printing and impression surfaces extend only part way around the circumference of the cylinder in each case, the rest of the cylinder being cut away, the web being carried on a reciprocating frame or gate which moves forward at a speed that will carry the paper through the printing point at the surface speed of the cylinders and which moves back at a quickened speed, the cylinders constantly revolving in the same direction at a uniform speed; the web, furthermore, being fed from the gate during the interval between printing operations. With respect to a press of this general character, whether the same be used for offset printing or not, the present invention has for objects to provide a novel mechanical movement for imparting motion to the gate in opposite directions at different speeds by which perfect accuracy is insured, and new and improved arrangements for feeding the web over the gate, which permits the web to be severed in sheets of any size, regardless of the size of the printed impressions, thereby making the press an all-size press, and which prevents any undue tautness or looseness of the web in the press.

The invention has for further objects such other new and improved constructions, arrangements and devices relating to printing presses, and particularly to rotary web presses, as will be hereinafter described and claimed.

The invention is illustrated in a preferred embodiment in the accompanying drawings, wherein—

Figure 1 is a longitudinal section taken through a press constructed in accordance with my invention, certain familiar parts being omitted for the purpose of clearness of illustration. Fig. 2 is a fragmentary sectional view illustrating the construction of the cylinders. Figs. 3, 4 and 5 are detail views, showing the parts in different positions, illustrating a mechanical movement for imparting motion to the gate in opposite directions at different speeds. Fig. 6 is a fragmentary view illustrating a portion of the mechanism for giving intermittent movement to the feed cylinders. Fig. 7 is a cross sectional view showing particularly the devices constituting the mechanical movement illustrated in Fig. 1 and Figs. 3 to 5 inclusive, and Fig. 8 is a detail end elevation of the forward feed cylinders and associated parts.

Like characters of reference indicate like parts in the several figures of the drawings.

Referring to the drawings, A, A designate the cylinders of the printing couple, B the paper roll, C the web, which, of course, is taken continuously from the roll, and D the reciprocating gate provided at opposite ends with rollers E, E', over which the paper runs.

F is a feed cylinder around which the paper passes before it goes over the gate, and F' is a feed cylinder around which the paper passes after leaving the gate.

G represents a shearing device, which may be of any desired sort, the same forming in itself no part of my invention, and H a receptacle for the sheets as they are cut from the web.

The cylinders A, A are formed with the coöperating portions 10, 10 which provide the impression and printing surfaces, the same, preferably, extending only half around the cylinders, the rest of the cylinders being cut away or recessed as indicated at 11. In order to adapt the press for printing by the offset method and on both sides of the web simultaneously, the cylindrical por-

tion of each of the cylinders is covered with a rubber blanket 12 (Fig. 2) of the sort ordinarily used on the printing cylinders of offset presses; and in such case each of the cylinders A, A is provided with its separate form cylinder, the form cylinders being designated J and being constructed in the familiar manner with portions of their surfaces adapted to receive ink from the inking mechanisms K, K and other portions adapted to be damped by the dampening mechanisms L, L. By this arrangement each printing surface constitutes an impression surface for the other printing surface. So far as I am aware, this arrangement is the first arrangement which has been devised for printing simultaneously at corresponding points on opposite sides of a web by the offset method.

The mechanism for imparting movement to the gate in opposite directions and at different speeds consists preferably of the following parts, it being understood that this mechanism might be employed for a press of this general character, whether or not it be so constructed as to print by the offset or surface method. The gate moves in guides 13, 13 and is provided with the racks 14, 14 (Fig. 7) which are meshed by pinions 15, 15, keyed to a shaft 16 which is mounted in the side frames 17, 17, the shaft 16 having keyed thereto a third pinion 18. One of the pinions 15 is meshed by a sector gear 19 which is pivoted at 20 to one of the frames 17. Pinion 18 is intermittently meshed by a sector gear 21, keyed to a shaft 22, which revolves in one of the frames 17, this shaft having keyed to it the driving gear 23, which receives movement from a pinion 24 on the first motion shaft 25, and being also provided with a crank 26 carrying a roller 27; the crank being so arranged on shaft 22 that the roller 27 which it carries enters a slide-way 28 formed radially on the oscillating sector 19 by means of the shoes 29, the upper ends of which are cut off obliquely, as indicated at 30, so as to guide the roller into the slide-way. The operation of this mechanism will be made apparent by referring to Figs. 3 to 5, which show the parts in three different positions. In Fig. 3 the rotating sector gear 21 is shown as just coming into a position in which it goes out of mesh with its pinion 18 (behind the pinion 15, see Fig. 7). The oscillating sector 19 is always in mesh with its pinion 15. A further rotation of gear 23 and sector gear 21 disengages the latter from pinion 18 and brings the roller 27 on crank 26 into the slide-way 28 on the oscillating sector gear 19. A further movement of rotation brings the parts into successively the positions shown in Figs. 5 and 4, causing the sector gear to be moved by a rapid motion toward the right, this relatively rapid mo-

tion being imparted to the gate, moving the latter in the same direction, that is to the right, as shown in Figs. 3, 4 and 5, and to the left, as shown in Fig. 1. The rotating sector gear 21 comes into mesh with the pinion 18 (Figs. 5 and 7) at the same time that the crank leaves slide-way 28. The movement imparted to the gate by the rotating sector gear 21, the forward movement through the printing point, is slower than the reverse movement just described, because of the difference in radius of the sector gear and crank 26. It will be seen that in its essential elements, this movement consists of a constantly rotating device which has intermittent engagement with the reciprocating device to move it in one direction at a relatively low and uniform speed, an oscillating member which engages the reciprocating device and is slidably engaged, during the intervals when said rotating device is inoperative, by a crank which rotates in unison with said rotating device; the oscillating member driving the reciprocating device in the opposite direction at a higher speed; a transmitting mechanism, pinions 15, 15, 18, shaft 16 being preferably interposed between the rotating device and oscillating member, and the reciprocating device.

The feed of the paper over the gate preferably takes place while the printing and impression cylinders present their recesses to each other and is accomplished by the following mechanisms; the roll B is uninterruptedly revolved by any desired means (not shown) and the web C unwound therefrom passes first around the rollers 31, then over a roller 32, a weight 33 being preferably placed in the loop c of the web between the rollers 31 and roller 32. From roller 32 the web passes over a roller 34 which is preferably slightly out of contact with the rear feed cylinder F. After being wrapped around cylinder F, the web passes over the rollers E, E' on the gate and then between feed cylinder F' and a roller 35, which preferably bears with some force against the paper on feed cylinder F'. The feed cylinders F, F' are of the same diameter and are geared together by means of the shaft 36 and bevel gears 37. Feed cylinder F' has loosely mounted thereon, a gear 38 which is meshed by a rack 39, guided so as to have vertical movement by the pins 40 which extend through slots 41 in said rack, and the rack is reciprocated by a connecting rod 42 and crank 42^a on a gear 43 which meshes with gear 23. The gear 38, loosely mounted on the cylinder F', has secured thereto pawl carrier 44 having a pawl 45 which engages a ratchet wheel 46 rigid with cylinder F' (Fig. 6). By this arrangement intermittent rotary motion is given to the feed cylinders F', F which, by a proper ad-

justment of the parts, may be timed so that it takes place during the intervals between successive printing operations.

As obvious modifications in form, construction and arrangement of the several devices and mechanism constituting the press of my invention, as above described, will readily suggest themselves to those skilled in the art of printing press construction, I do not limit myself to these particulars except so far as certain of the claims herein are limited thereto.

I claim:

1. In a web press, the combination with printing means, of a gate which supports the web, and mechanism for imparting movement to said gate in opposite directions at different speeds comprising a rack on said gate, a pair of pinions connected so that they rotate together, one of said pinions meshing with said rack, a sector gear which has constant rotation and which intermittently meshes with one of said pinions, an oscillating sector gear of greater radius which meshes with the other of said pinions, a radial slide-way on said oscillating sector gear and a crank rotating in unison with said rotating sector gear constructed so that it slidably engages with the slide-way on said oscillating sector gear, while the rotating sector gear is out of mesh with its pinion.

2. In a printing press, the combination with printing elements formed with co-acting surfaces and with recesses between said surfaces, of a reciprocating gate which carries said web through the printing point and which is returned after each forward movement by a return movement at an increased speed, and means for feeding said

web from said gate at intervals between printing operations comprising a feed cylinder arranged in advance of said gate, a feed cylinder arranged back of said gate, said cylinders being geared together, means for intermittently driving said cylinders, a roller bearing against the forward feed cylinder, the web being loosely wrapped around the rear cylinder, supporting means for said web back of said rear feed cylinder, said means comprising supporting devices spaced apart between which the web may be looped, and a weight in said loop of the web.

3. In a printing press, the combination with printing elements formed with co-acting surfaces and with recesses between said surfaces, of a reciprocating gate which carries said web through the printing point and which is returned after each forward movement by a return movement at an increased speed, and means for feeding said web from said gate at intervals between printing operations comprising a feed cylinder arranged in advance of said gate, a feed cylinder arranged back of said gate, said cylinders being geared together, means for intermittently driving said cylinders, a roller bearing against the forward feed cylinder, the web being loosely wrapped around the rear cylinder, supporting means for said web back of said rear feed cylinder, said means comprising supporting devices spaced apart between which the web may be looped, and a weight in said loop of the web, said web adapted to be constantly fed to said supporting means.
